No. 37,261.

Patented December 13, 1904.

UNITED STATES PATENT OFFICE.

WILLIAM J. DIETRICH, OF NEW YORK, N. Y., ASSIGNOR TO AMERICAN CAN COMPANY, OF NEW YORK, N. Y., A CORPORATION OF NEW JERSEY.

DESIGN FOR AN ADVERTISING-LABEL.

SPECIFICATION forming part of Design No. 37,261, dated December 13, 1904.

Application filed October 8, 1904. Serial No. 227,728. Term of patent 14 years.

To all whom it may concern:

Be it known that I, WILLIAM J. DIETRICH, a citizen of the United States, residing in the borough of Brooklyn, city of New York, in the county of Kings and State of New York, (whose post-office address is 11 Broadway, New York city,) have invented a new, original, and ornamental Design for an Advertising - Label shown in the accompanying drawing, forming part of this specification.

The figure of the drawing is a plan view of an advertising-label, showing my new design.

I claim—

The ornamental design for an advertising-label as shown.

WILLIAM J. DIETRICH.
